UNITED STATES PATENT OFFICE.

MILTON H. BALLARD, OF LYNN, MASSACHUSETTS, ASSIGNOR TO TRIPP FRUIT WRAPPING MACHINE COMPANY, OF LYNN, MASSACHUSETTS, A CORPORATION OF MAINE.

FEEDING DEVICE FOR PAPER.

No. 847,977.

Specification of Letters Patent.

Patented March 19, 1907.

Original application filed February 13, 1904, Serial No. 193,392. Divided and this application filed October 2, 1905.
Serial No. 280,909.

To all whom it may concern:

Be it known that I, MILTON H. BALLARD, of Lynn, county of Essex, State of Massachusetts, have invented an Improvement in Feeding Devices for Paper, of which the following description, in connection with the accompanying drawings, is a specification, like characters on the drawings representing like parts.

10 This application is a division of my application, Serial No. 193,392, filed February 13, 1904.

In certain forms or types of wrapping-machines—such, for instance, as shown in Letters Patent No. 472,202, dated April 5, 1892—paper in strip form is drawn from a roll by means of devices which act to feed it to the severing devices, which sever the strip, and thereby produce wrappers of suitable size to 20 be used for wrapping oranges and other things. The feeding devices act intermittently and also rapidly, and when they start from a position of rest they violently pull upon the strip of paper and suddenly start 25 the paper-carrying roll revolving, and when they cease said roll continues to revolve for a short period of time by momentum, unreeling a considerable length of paper. An attempt has been made to check rotation of the paper-carrying roll when the intermittently-operated means employed to draw off the paper cease to operate and to take up the slack paper incident to the roll continuing to 30 revolve for a short period of time—as, for instance, as shown in Letters Patent No. 35 516,136, dated March 6, 1894—wherein a locking device is provided for engaging, and thereby suddenly checking, rotation of the roll, and a take-up device is also provided for 40 taking up the slack paper, the locking device being operated by the take-up device. In practice, however, this means is objectionable, for the reason that the paper-carrying roll is free to revolve until suddenly stopped 45 and acts during such time to unreel the paper, and as a result more paper is unreeled than can be taken up by the take-up device during the short time it is permitted to act, as the locking device, which is operated by 50 the take-up device, will engage the roll and stop it suddenly with considerable shock and jar before the slack is all taken up.

This invention has for its object to provide means for taking up the slack paper incident to the paper-carrying roll continuing to revolve after the feeding-rolls or other intermittently-operated means which may be employed for drawing the paper from the roll have ceased to operate and to hold said slack paper taut, and to provide brake mechanism 55 for the paper-carrying roll, which begins to act as soon as the intermittently-operated means ceases to operate, to slowly check rotation of said roll, and by thus retarding the roll to reduce the amount of slack to the minimum. Some slack is very desirable, for the reason that the feeding-rolls or other intermittently-operated means are thereby permitted to more easily start from a position of rest; but by the employment of my invention 60 the slack is reduced to the amount required for this purpose and is held taut.

Figure 1 shows a sufficient portion of a wrapping-machine to illustrate the paper-feeding devices embodying my invention, 75 the full lines representing the feeding devices at rest and the brake applied to the paper-carrying roll and the slack all taken up by the take-up device and held taut and the dotted lines representing the paper while being drawn from the roll, the take-up device 80 acting at such time to apply a tension to or upon the strip and the roll being free to revolve. Fig. 2 is a plan view of the paper-carrying roll, brake mechanism therefor, and 85 the take-up device, and Figs. 3 and 4 are details of the intermittently-operated means which may be employed for drawing the paper from the roll.

The intermittently-operated means by 90 which the paper is drawn from the paper-carrying roll is herein shown as a pair of feeding-rolls and means for operating them, such intermittently-operated means being shown herein merely for the sake of illustrating my 95 invention, as, so far as my invention is concerned, any other form of intermittently-operated means may be employed.

41 represents the upper roll, which is supported in suitable bearings and has secured to 100 it at one end a toothed gear 51, and 42 represents the lower roll, which is also supported in suitable bearings and has secured to it at one end a toothed gear 52. The gear 52 engages

the gear 51. Hence one of the rolls will be positively driven by the other. A pinion 53 is loosely mounted on the shaft of the lower roll, bearing one or more pawls 58, which engage 5 the teeth of a ratchet-wheel 59, which is secured to said roll, and said pinion 53 is engaged by a rack 54, which is supported by suitable bearings. The rack 54 is loosely connected at one end to an upright bar 55, pivoted at 10 its lower end to the main frame. Near the lower end of the bar 55 a lateral extension 56 is provided, having a curved slot, and a bar 57 is adjustably connected at one end to said slotted extension 56, its opposite end being 15 connected to an eccentric on the main shaft f^s . As the shaft f^s revolves the bar 57 is reciprocated and the rack-bar 54 is correspondingly moved, and the feeding-rolls or other intermittently-operated means are operated 20 to draw the paper from the paper-carrying roll.

i^2 represents the paper-carrying roll, the shaft of which is journaled in suitable bearings on the frame, and to said shaft at one end of the roll a brake-wheel 28 is secured. 25 A brake-band 35 is provided for said brake-wheel, one end of which is attached to a fixed point on the frame close to the brake-wheel, as at 36, and the other end is attached to one end of a short bar or pin 29, which extends 30 through a hole in an arm 30, which is pivoted at 31 to the frame at a point remote from the point of attachment of the brake-band. The brake-band is made long enough to partially surround the brake-wheel, and the bar 35 or pin 29 loosely fits the hole in the arm, so that it is free to slide therein or when held against longitudinal movement permits the arm to move upon it. Between the end of the bar or pin 29, to which the brake-band is 40 attached, and the arm 30 a spiral spring 37 is provided, which surrounds the bar, bearing at one end against the arm 30 and at the other end against an enlargement or shoulder which is formed or provided at the extremity of the 45 bar. The free end of the brake-band is thus yieldingly connected with the arm 30. The arm 30 is movable on its pivot toward and from the brake-wheel, having a rising-and-falling movement, and operates to wind the 50 brake-band upon the brake-wheel when falling and to unwind it therefrom when rising, and when the brake-band is wound upon the brake-wheel said arm continues to fall, compressing the spring 37, thereby operating to 55 apply a gradually-increasing pressure upon or to the free end of the band.

At the opposite end of the paper-carrying roll a similar pivoted arm 30 is provided, and the two arms 30 are joined together by a rod 60 or bar upon which a roll 32 is free to revolve. This roll serves as the take-up roll for the slack paper and together with its support forms the take-up device. The strip of paper from the paper-carrying roll passes 65 under the take-up roll 32, thence over a roll

33, supported in fixed bearings on the frame, and thence to the intermittently-operated means employed for drawing the paper from the paper-carrying roll. The operation is as follows: As the feeding-rolls or other intermittently-operated means start from a position of rest the slack paper, which is held taut by the take-up device, is drawn up, lifting the take-up roll and moving the arms 30 on their pivots, and thereby unwinding the 70 brake-band from the brake-wheel 28 and leaving the paper-carrying roll free to revolve as the paper is drawn from it. As soon as the intermittently-operated means cease to operate the paper-carrying roll continues to revolve by momentum; but the take-up roll 32, which is supported in elevated position by the paper, settles down by gravity and takes up the slack paper, the arms 30 moving on their pivots. The brake-band is wound upon the brake-wheel and pressure applied to its free end by the gravitating movement of said take-up device. The pressure upon the brake-band and its area of contact with the brake-wheel is slight 80 at first, but sufficient to retard the roll, and as the gravitating movement of the take-up device continues the area of contact of the brake-band with the brake-wheel gradually increases until said brake-band is entirely in engagement therewith, as shown in full lines, Fig. 1, and then the weight of the take-up device acts upon and compresses the spring 37, and thereby acts gradually to increase the pressure of the brake-band upon the brake-wheel. The parts soon come to rest and the slack produced is all taken up by the take-up device, so that at all times the paper is held 90 taut or under tension. It will be seen that the brake mechanism thus described is accumulative, acting with a gradually-increasing force, and that it begins to act when the take-up device begins to fall, and, furthermore, it will be seen that the take-up device is controlled or operated by the means employed for drawing off the paper and also that said device serves as the operating means or device for the brake mechanism.

Brake mechanism for the paper-carrying roll, which operates accumulatively to gradually retard and finally stop the roll, as contrasted to a positive locking device, is an important feature of my present invention, and so, also, is the take-up device, which serves to take up the slack paper and also to hold the slack paper taut, and also constitutes the means for operating the brake mechanism, which is controlled by the means employed for drawing off the paper; but other forms of brake mechanism acting accumulatively substantially as herein shown and other means for operating said brake mechanism may be employed in lieu of the particular forms herein shown without departing from the spirit and scope of my invention.

Having thus described my invention, what I claim as new, and desire to secure by Letters Patent, is—

1. In a paper-feeding device, the combination of a paper-carrying roll having a brake-wheel, a brake-band attached at one end at a point near the brake-wheel, and means, connected with the free end of said band, for holding it taut, and for winding it, while thus held taut, upon said brake-wheel, to thereby retard the brake-wheel by a gradually-increasing force corresponding to the gradually-increasing area of the band in contact therewith, the operation of said means being controlled by the web of paper drawn from the roll, substantially as described. 10
2. In a paper-feeding device the combination of a paper-carrying roll having a brake-wheel, a brake-band attached at one end at a point near the brake-wheel, and means, connected with the free end of said band, for holding it taut, and for winding it, while thus held taut, upon said brake-wheel to thereby retard the brake-wheel by a gradually-increasing force corresponding to the gradually-increasing area of the band in contact therewith, and for subsequently applying a gradually-increasing pressure to said band, the operation of said means being controlled 25 by the web of paper drawn from the roll, substantially as described. 30
3. In a paper-feeding device, the combination of a paper-carrying roll having a brake-wheel, a brake-band attached at one end at a point near the brake-wheel and adapted to be wound upon said brake-wheel to thereby act with a gradually-increasing force, a pivoted arm to which the free end of said brake-band is attached and by which it is held taut 35 and moved in a circular path about the brake-wheel while winding it thereon, and a paper-engaging roll borne by said arm adapted to engage the web of paper and thereby control the movement of said arm, substantially as 40 described. 45
4. In a paper-feeding device, the combination of a paper-carrying roll having a brake-wheel, a brake-band attached at one end at a point near the brake-wheel and adapted to be wound on said brake-wheel to thereby act with a gradually-increasing force, a pivoted arm to which the free end of said brake-band is 50 yieldingly connected and by which it is moved in a circular path about the brake-wheel while winding the brake-band thereon, and also by which a gradually-increasing pressure is applied to the brake-band when the latter is wound upon the brake-wheel and a paper-engaging roll borne by said arm 55 adapted to engage the web of paper to thereby control the movement of said arm, substantially as described. 60
5. In a paper-feeding device, a paper-carrying roll having a brake-wheel, a brake-band, one end of which is attached to a fixed 65 point close to the brake-wheel, and a rising-and-falling member to which the free end of said band is yieldingly connected, which is constructed and arranged to wind said band upon the brake-wheel when falling, and to 70 unwind it therefrom when rising, and also to apply a gradually-increasing pressure to the free end of said band when the latter is wound upon the brake-wheel, and a paper-engaging roll borne by said member adapted to engage 75 the paper drawn from the paper-carrying roll and thereby control the movements of said member, substantially as described. 80
6. In a paper-feeding device, a paper-carrying roll having a brake-wheel, a brake-band, one end of which is attached to a fixed point close to the brake-wheel, and a rising-and-falling member to which the free end of said band is yieldingly connected, which is constructed and arranged to wind said band 85 upon the brake-wheel when falling, and to unwind it therefrom when rising, and also to apply a yielding pressure to the free end of said band when the latter is wound upon the brake-wheel, and a paper-engaging roll borne 90 by said member adapted to engage the paper drawn from the paper-carrying roll and thereby control the movements of said member, substantially as described. 95
7. In a paper-feeding device, a paper-carrying roll, having a brake-wheel, a brake-band attached at one end at a point near the brake-wheel, an arm extending from one side of said paper-carrying roll to the opposite side thereof having a paper-engaging roll at 100 one end adapted to engage the web of paper near the paper-carrying roll and having its opposite end pivoted at a point remote from the brake-wheel and from the point of attachment of the brake-band, the free end of 105 said brake-band being connected to said arm at an intermediate point whereby the brake-band is wound upon and unwound from said brake-wheel by the arm moving on its pivot and moving the free end of the brake-band in 110 a circular path about the brake-wheel, substantially as described. 115
8. In a paper-feeding device, a paper-carrying roll having a brake-wheel, a brake-band, attached at one end to a point near the 120 brake-wheel, an arm having a paper-engaging roll, pivoted at a point remote from the brake-wheel and from the point of attachment of the brake-band, to which the free end of said band is connected, and by which the brake-band is wound upon and unwound from the brake-wheel, substantially as described. 125
9. In a paper-feeding device, a paper-carrying roll having a brake-wheel, means for drawing the paper from the roll, a pivoted arm bearing a take-up roll, a bar slidably connected with said arm, a brake-band for said brake-wheel, one end of which is attached to a fixed point and the other end to 130

said bar, and a spring on said bar between the arm and the end of the bar, substantially as described.

10. In a paper-feeding device, a paper-carrying roll having a brake-wheel, means for drawing the paper from the roll, a pivoted arm bearing a take-up roll, a bar yieldingly supported by said arm, a brake-band for said brake-wheel, one end of which is attached to a fixed point and the other end is attached to said bar, substantially as described.

11. In a paper-feeding device, a paper-carrying roll having a brake-wheel, a pivoted arm having a paper-engaging roll for engag-

ing the web of paper drawn from the paper-carrying roll, a bar slidably connected with said arm, a spring acting to thrust said bar outward, and a brake-band for said brake-wheel, one end of which is attached to a fixed point and the other end is attached to said sliding bar, substantially as described.

In testimony whereof I have signed my name to this specification in the presence of two subscribing witnesses.

MILTON H. BALLARD.
